United States Patent Office

Des. 177,641
Patented May 8, 1956

177,641

BATHROOM SCALE

Harry Preble, Jr., Cross River, N. Y., assignor to Detecto Scales, Inc., Brooklyn, N. Y., a corporation of New York

Application February 9, 1955, Serial No. 34,430

Term of patent 14 years

(Cl. D52—10)

Fig. 1

Fig. 2

Fig. 3

Fig. 4

Fig. 1 is a top plan view of a bathroom scale, showing my new design;

Fig. 2 is a side elevational view thereof;

Fig. 3 is a front elevational view thereof; and

Fig. 4 is a rear elevational view thereof.

I claim:

The ornamental design for a bathroom scale, substantially as shown.
